UNITED STATES PATENT OFFICE

LACASSE ROUSSEAU, OF MONTMAGNY, QUEBEC, CANADA

ARTICLE-PACKING STRIP

Application filed September 5, 1929. Serial No. 390,636.

The present invention relates to a packing strip, and more particularly to a kind adapted to hold a number of small, substantially flat articles in a closely related condition.

5 In the manufacture of furniture, use is made of a metal stamping which is pointed at one end and is used to limit the movement of drawers; said stampings being called "drawer stops" and being forced into the 10 wood by suitable machinery.

Heretofore, the said stops were inserted in the machine one by one or at least only a few at a time, and they were delivered or sold in bulk.

15 According to the present invention, a special container has been devised which conveniently holds about 200 of said stops in a most compact manner, and in such a way that the whole number thereof can be inserted 20 in the machine at one time, thereby saving time and labor.

Accordingly, the main object of the invention may be stated to reside in the provision of a special container whereby metal drawer 25 stops can be conveniently delivered and utilized.

Another object of the invention is the provision of a package for metal drawer stops which is convenient and cheap of manufac- 30 ture.

As an example, and for purposes of illustration, a preferred embodiment of the invention is shown in the annexed drawings, wherein:

35 Figure 1 is a perspective view of the strip without the stops,

Figure 2 is an enlarged view showing the stops in the strip,

Figure 3 is an end view thereof,

40 Figure 4 is a detail of the strip fastening means, and

Figure 5 is a perspective view of the stop proper.

Referring to the drawings, wherein similar 45 reference numerals represent corresponding

parts throughout, numeral 10 designates the drawer stop, shown in Figure 5, and a number of which are shown also in Figure 2.

A bottom strip 11, of concave shape and of elongated formation, has stamped therefrom a plurality of lugs 12 for securing the cover 13 of the package. As shown to advantage in Figures 1 and 4, said cover is angularly formed and is similar to a pyramid in appearance. Apertures 14 are provided in the said cover to receive the lugs 12 which are bent over, as shown at Figure 4, for securing purposes.

As clearly demonstrated in Figure 2, the respective shapes of the bottom strip and cover are so chosen as to snugly engage the stops 10 to prevent rattling thereof in the package.

The advantage of this type of packing resides mostly in the facility with which a drawer stop inserting machine can be filled with about 200 stops at one time, and without labor or trouble. When it is desired to open the strip, it is only necessary to break or straighten the bent part 15 of the lugs 12, 70 so that the cover can be removed and the stops inserted in the machine directly from the package.

From the foregoing description, it will be apparent that the packing strip object of 75 the present invention is a most useful container for a specific article, and that the construction thereof enables quantities of stops to be shipped and inserted at once in a machine with a minimum amount of trouble and 80 a considerable saving in time.

It must be understood that various alterations as to size and shape of the invention can be resorted to without departing from the spirit of the invention or the scope of the 85 subjoined claim.

Having thus described my invention, I claim:

A packing strip for containing metal drawer stops in a stacked position, comprising a 90

concave bottom member of elongated formation, a plurality of lugs stamped from the central portion of the member and extending at right angles therefrom, and a cover member bent longitudinally at substantially right angles having apertures to receive the ends of the lugs and to be secured in closely related position against the drawer stops resting in the bottom member by bending the end portion of the lugs against the top member.

10 In witness whereof I have hereunto set my hand.

LACASSE ROUSSEAU.
